FRIED. KRUPP AKTIENGESELLSCHAFT GRUSONWERK, OF MAG-
DEBURG-BUCKAU, GERMANY.

MEANS FOR COOLING GUN-BARRELS.

No. 799,476.

Specification of Letters Patent.

Patented Sept. 12, 1905.

Application filed May 2, 1904. Serial No. 206,045.

To all whom it may concern:

Be it known that I, HERMANN LEHMAN, a subject of the King of Prussia, German Emperor, and a resident of Magdeburg, Kingdom of Prussia, Empire of Germany, have 5 invented a new and useful Improvement in Means for Cooling Gun-Barrels, of which the following is a specification.

This invention has for its object a device 10 for effectually cooling the exterior of the barrels of ordnance, quick-firing guns, and firearms whereby at each discharge an air-pump is actuated and forces atmospheric air into a reservoir; whence said air is brought into 15 contact with the barrel through a number of nozzles. The compressed air carries along with it the air surrounding the nozzles, and thereby produces an extremely energetic movement of the surrounding air along the 20 surface of the barrel, thus effectually cooling it.

In order that the said invention may be clearly understood and readily carried into effect, the same will be described more fully 25 with reference to the accompanying drawings, in which—

Figure 1 is a longitudinal section of a quick-firing gun of the sliding-barrel type provided with the cooling device. Fig. 2 is a 30 plan of the same. Fig. 3 is a cross-section on the line A B, and Fig. 4 a cross-section on the line C D. Fig. 5 is an end view of the barrel as seen from the muzzle. Fig. 6 is an enlarged sectional view through one of the 35 nozzles and a portion of one of the tubes.

To the barrel *a* (which in the drawings is shown in its retracted or recoiled position,) the air-pump piston *b* is connected. The cylinder for this piston is rigidly connected with 40 the casing *d*, which does not participate in the recoil. The breech mechanism of the gun is not represented in the drawings, as it is immaterial to the device which forms the subject of the invention. The barrel is returned 45 to battery by means of the recoil-spring *e*. On discharge of the gun the barrel *a*, which is exposed to the atmosphere, recoils, and the piston *b* compresses the air which is behind it, thus forcing said air past a valve *i*, 50 Fig. 3, into the air-reservoir *f*, which is connected with the casing *d*. From this reservoir the air passes through a pipe *h*, a reservoir the air passes through a pipe *h*, a distributing-passage *g*, and tubes *l*, situated

around the gun-barrel, to the nozzles *m* of these tubes, the said air escaping from these 55 nozzles onto the surface of the gun-barrel. The said nozzles, which are shown on a larger scale in Fig. 6, project laterally from the tubes *l* and should be obliquely directed toward the muzzle of the gun-barrel. The air 60 issues from the small outlet-apertures of the nozzles with great velocity, and consequently carries with it against the surface of the gun-barrel the surrounding outer air, so that the barrel is effectually cooled. During the recoil air is also sucked through a valve *k* into the cylinder *c* in front of the piston *b*, which air as the barrel regains its firing position reaches the nozzles by the path already described. As the sum of the cross-sections 65 of the nozzles is smaller than the cross-section of the air-pump, the pressure in the air-reservoir will gradually increase. During the first few discharges of the gun air will only issue from the nozzles intermittently; 70 but if the shooting is long continued the periods during which air will issue from the nozzles become longer, until finally when the pressure has become sufficiently high an uninterrupted stream of air escapes from the 75 nozzles. As already stated, the nozzles should be directed toward the muzzle, so that the current of air flows along the barrel and passes through the openings *o* in the end piece or ring connecting the nozzle-tubes *l*, and thus 80 passes over the muzzle, from which it drives the powder-gases. In ordnance or firearms in which the barrel does not recoil any other moving part of the gun, such as the breech-screw or breech-block, may be connected with 85 the air-pump piston, or the air may be compressed by the energy of the powder-gases operating through the intermediary of a working cylinder.

I claim—

1. In a gun, the combination with the barrel, of a series of nozzles directing air on the exterior of the barrel and means for forcing air through the nozzles.
2. In a gun, the combination with the barrel, of a series of nozzles directing air on the exterior of the barrel and in the direction of the muzzle and means for forcing air through the nozzles.
3. In a gun, the combination with the barrel, of a tube extending longitudinally of the

barrel and directing air on the barrel at a plurality of points throughout the length of the barrel and means for forcing air through the tube.

5. 4. In a gun, the combination with the barrel, of a tube extending longitudinally of the barrel and provided with a plurality of nozzles throughout its length directing air in the direction of the muzzle and means for forcing air through the tube.

5. The combination with the gun-barrel exposed to the atmosphere, of means directing compressed air along the exposed part of the barrel, in a manner to produce a movement 15 of the surrounding air along the barrel in the direction of the muzzle.

6. The combination with the gun-barrel exposed to the atmosphere, of means operated by the recoil of the barrel for directing com-

pressed air along the exposed part of the barrel, in a manner, to produce a movement of the surrounding air along the barrel in the direction of the muzzle.

7. The combination with the gun-barrel, of a series of nozzles arranged around the barrel and directing air thereon, and means for forcing air through the nozzles.

8. The combination with the gun-barrel, of a series of nozzles arranged along and around the barrel and directing air thereon, and means 30 for forcing air through the nozzles.

The foregoing specification signed this 12th day of April, 1904.

HERMANN LEHMANN.

In presence of—

WILHELM FLEISCHBACK,
JAMES L. A. BURRELL.
